(57) CLAIM

The ornamental design of an alphanumeric typeface or font, as shown and described.

DESCRIPTION

FIG. 1 is a face view of the alphabetic symbols of an alphanumeric typeface or font showing our new design; and, FIG. 2 is a face view of the numeric symbols of the alphanumeric typeface or font of FIG. 1. The letters, numbers and the parentheses in which they are enclosed shown in broken lines in the drawings form no part of the claimed design.

1 Claim, 1 Drawing Sheet
